(57) **CLAIM**

The ornamental design for a safety seat, as shown and described.

DESCRIPTION

FIG. 1 is a front, top, and right perspective view of a safety seat according to our new design;

FIG. 2 is a rear, top, and left perspective view;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof; and,

FIG. 9 is front, top, and right perspective view of the safety seat shown in FIG. 1, illustrating the footrest flipped to a horizontal state.

The broken (dashed) lines show portions of the safety seat that form no part of the claimed design.
